(57) CLAIM

The ornamental design for a therapeutic pillow, as shown and described.

DESCRIPTION

FIG. 1 is a front side perspective view of a therapeutic pillow showing my new design;

FIG. 2 is an elevational view of one end of the therapeutic pillow shown in FIG. 1, the opposite end being a mirror image of that shown in FIG. 2;

FIG. 3 is a front elevational view thereof;

FIG. 4 is a rear elevational view thereof;

FIG. 5 is a top plan view thereof; and,

FIG. 6 is a bottom plan view thereof.
